UNITED STATES PATENT OFFICE.

JOAQUIN CUSI, OF BUENOS AIRES, ARGENTINA.

POCKET PROTECTOR FOR CHECKS AND THE LIKE.

Application filed May 1, 1923. Serial No. 635,834.

To all whom it may concern:

Be it known that I, JOAQUIN CUSI, a subject of the King of Spain, residing at 630 5 Luiipacha Street, Buenos Aires, Republic of Argentina, have invented new and useful Improvements in Pocket Protectors for Checks and the like, of which the following is a specification.

This invention relates to a pocket protector for checks, drafts, and like documents, its main object being to provide an apparatus of a very simple construction, which is of a very low cost and reduced size, which can be carried in the pocket and by 10 means of which checks and like documents may be provided with perforated control characters or signs, such as numerals and the like so as to avoid any alteration of the same.

Another object of my present invention consists in providing an apparatus of the above nature with means which allow a regulation as to the general and relative position of the controlling characters or 15 signs.

The invention has other objects in view which will appear hereafter and which are clearly set forth in the appended claiming clauses.

In order that my present invention may be clearly understood and easily carried into practice a preferred embodiment of the same is shown in the accompanying drawings. However, it must be clearly understood that the scope of the invention is 20 in no way limited to the specific form illustrated and described and that many formal and constructional changes may be introduced without departing from the scope of my said invention, which is clearly set forth in the appended claiming clauses.

In the said drawings,

Figure 1 is a partly sectional side elevation of a device constructed according to my 25 present invention.

Fig. 2 is a transverse section of Figure 1 which shows a detail of one of the perforating elements and of the push button.

Fig. 3 is a perspective view of the apparatus in operative position, said apparatus being provided with a suitable form of guiding means for the support and movement of the document to be protected and

Fig. 4 is a like view which shows the device in part and illustrates another form of guiding and positioning device.

Similar characters of reference denote same or like parts throughout the said drawings.

In the embodiment shown, the main body 60 of the apparatus which is of an elongated rectangular form, consists of three superposed parts in its whole length; an upper part 1 which forms a cover, an intermediate part in the form of a box as shown at 2, 65 which contains the perforating devices and a lower part 3 soldered at one end to the bottom of the box 2 with an intermediate space 5 through which the document to be perforated may slide. 70

The cover 1 has a series of orifices 6 of a circular or other convenient shape which are conveniently disposed at the same distances apart and on the whole length of the cover so as to permit the action as hereinafter explained of the perforating devices within the box 2, said devices being capable of independent operation one from the other. Within the box 2 and corresponding with the said orifices 6 there are 75 a number of housings 7 open at their upper and lower ends and having at the former an inwardly turned flange 8. Said housings are fixed by their bottom edges to the bottom of the box 2. Within each housing is 80 a metallic disc or the like 9 which on its lower face carries a number of thin bars or needles 10 suitably disposed so as to form a number, letter or other suitable character or sign. A coil spring 11 is placed within 85 the housing around the said needles and presses the disc 9 against the flange 8, as will be seen from Figures 1 and 2. The bottom of the box 2 and the part 3 of the main body of the apparatus are provided 90 with series of small orifices which exactly correspond as to position and size to the bars or needles 10, so that by pressing on the discs 9 the bars or needles 10 pass through the orifices 12 of both the said elements. It is obvious from the foregoing 95 that when introducing a piece of paper or any other perforatable material in the free space 5 and positioning it suitably under one of the discs 9, on exerting pressure on the said disc the paper or other object will be perforated and indelibly marked with the sign, number or letter corresponding to the said disc. On their outer faces the discs 9 may be provided with a suitable indication of the corresponding sign. 100

The pressure on the discs 9 against the

action of the springs 11 which tend to push them against the upper flange 8 of the housings 7 may be exerted either by a push button or the like fixed to each of them or preferably by means of a common push button 5 slidably mounted on the apparatus, as shown in the drawings. In the embodiment shown the body 1 carries along its side a protruding guide 13 on which a correspondingly 10 shaped portion of a support 14 may slide. Said support carries a box 15 on which the actuating button is fixed. Said button consists of two oppositely inverted thimbles or caps 16 and 17 with outwardly turned edges 15 which are secured between the inwardly turned edges of the box 15. Both thimbles 16 and 17 are separated by means of a spring 18 which tends to keep them apart and allows a double movement so as to permit 20 the lower thimble 17 to be raised during the sliding movements of the button along the device and said lower thimble 17 to be pressed downwards when after pressing the spring 18, the upper thimble 16 rests on the 25 edge of the lower thimble. The play of the lower thimble 17 within the case 15 determines the run of the needles or bars 10. It is obvious that on sliding the button 16 and its box 15 until it corresponds with the selected disc 9 and bringing the document to 30 a corresponding position, on pushing down the button 16 the perforation of the document is obtained and on repeating said operation groups of numbers or other suitable 35 signs will be obtained which allow a perfect identification of the said document.

As the placing by hand of the document in the free space 5 and the successive movements of the same therein in order to produce 40 the series of perforated controlling indications may give rise to many irregularities of distance and alignment, many different guiding and supporting devices may be used in combination with my present apparatus. It must be however clearly understood that the invention is not limited to any specific guiding means, those illustrated being given only as an example of execution.

In the embodiment shown in Figure 3 the 50 guiding device consists of a metallic plate of an elongated rectangular shape 20 having a longitudinal slot 21 said slot being provided with a series of equidistant divisions 23 which correspond to the distance between 55 the signs. Said plate is partially bent over and has a number of tongues 22 so as to tightly hold the document or other paper as shown in the drawings. The plate is inserted in a guide 19 formed in the support 14 60 of the push button 16 so that on sliding said button on the guide 13 in order to bring it to the desired position, said button may carry with it the guide 20 and the document held thereby. The transverse sliding of the 65 piece 20 with respect to the guide 19 together

with the indications in the scale 23 permit of a regular spacing of the signs in perfect alignment.

Another embodiment of a supporting and guiding device is illustrated in Figure 4. Said device consists of a casing 27 carrying at its lower end a plate 28 which serves as a support for the document whereas at the upper part it carries an elongated plate 26 having a spring leaf which passes through a recess in a lateral guiding member 24 formed in the support 14 of the button. The said spring is designed to hold the guide in position and to determine the marginal space to be left in each case. The casing 75 carries a stub shaft 29 which has a toothed wheel 30 and a screw button 31 so that on having the document pressed in the box between the plate 28 and the said wheel, as shown in Figure 4, by giving the said wheel 80 a rotary motion through a predetermined angle an exactly regulable advance of the document may be obtained for a regular spacing of the signs. The advance from 85 sign to sign along the device 1 is made as 90 hereinbefore explained.

It is obvious that many formal and constructional changes may be introduced without departing from the scope of my present invention.

What I claim and desire to secure by Letters Patent is:

1. A protector for checks and other documents comprising an enclosing casing, a series of guiding housings disposed therein, a vertically movable disc in each housing, a series of perforating devices projecting downwardly from each disc, the devices of each disc differing in disposition from those of the other discs to produce a plurality of 100 different characters or signs, a spring encompassing each series of devices, a member arranged beneath said casing but spaced therefrom to permit the introduction of a 105 document between said casing and member and having openings in line with the perforating devices, a member movable longitudinally of the casing adapted to operate the different discs to perforate a document with 110 different characters, there being openings in 115 the casing to permit said member to contact with the different discs and means for properly positioning a document below the different series of perforating devices.

2. A protector for checks and other documents comprising an enclosing casing, a series of guiding housings disposed therein, a vertically movable disc in each housing, a series of perforating devices projecting downwardly from each disc, the devices of each disc differing in disposition from those of the other discs to produce a plurality of 120 different characters or signs, a spring encompassing each series of devices, a member arranged beneath said casing but spaced 125 130

therefrom to permit the introduction of a document between said casing and member, and having openings in line with the perforating devices of the various characters, a box-like member superimposed on the casing and adapted to be moved to engage said discs through openings in the casings, guiding means on said casing, co-operating guides on said box-like member, a pair of oppositely inverted caps or thimbles retained in said box-like member, a spring for forcing said caps apart, and means for indicating the position of the document to be or being perforated with relation to the desired series of perforating devices. 10
5 In testimony whereof I have signed my name to this specification. 15

JOAQUIN CUSI.
